CLAIM

The ornamental design for a cross slit gasket for introducer sheath, as shown and described.

DESCRIPTION

FIG. 1 is a perspective view the cross slit gasket for introducer sheath.

FIG. 2 is a top view of the cross slit gasket for introducer sheath of FIG. 1.

FIG. 3 is a bottom view of the cross slit gasket for introducer sheath of FIG. 1.

FIG. 4 is a side view of the cross slit gasket for introducer sheath of FIG. 1.

FIG. 5 is a cross sectional view of the cross slit gasket for introducer sheath of FIG. 1. The cross sectional view of FIG. 5 is taken along the longitudinal length of slit of FIG. 2; and, FIG. 6 is a cross sectional view of the cross slit gasket for introducer sheath of FIG. 1. The cross sectional view of FIG. 6 is taken along the longitudinal length of slit of FIG. 3. The cross section view of FIG. 6 is perpendicular to the cross sectional view of FIG. 5.

1 Claim, 6 Drawing Sheets
